CLAIM

The ornamental design for a headband for head mount display, as shown and described.

DESCRIPTION

FIG. 1 is a perspective view of a headband for head mount display showing our new design;

FIG. 2 is another perspective view thereof;

FIG. 3 is still another perspective view thereof;

FIG. 4 is yet another perspective view thereof;

FIG. 5 is a front view thereof;

FIG. 6 is a rear view thereof;

FIG. 7 is a left side view thereof;

FIG. 8 is a right side view thereof;

FIG. 9 is a top view thereof;

FIG. 10 is a bottom view thereof; and,

FIG. 11 is a perspective view thereof, shown in an environment of use.

The dashed broken lines illustrate portions of the headband for head mount display and form no part of the claimed design.
